UNITED STATES PATENT OFFICE.

GEORGE WARREN DREW, OF SAN FRANCISCO, CALIFORNIA.

CARPENTER'S VISE.

SPECIFICATION forming part of Letters Patent No. 729,741, dated June 2, 1903.

Application filed July 2, 1902. Serial No. 114,041. (No model.)

To all whom it may concern:

Be it known that I, GEORGE WARREN DREW, a citizen of the United States, residing at San Francisco, in the county of San Francisco and State of California, have invented certain new and useful Improvements in Carpenters' Vises, of which the following is a full and complete specification, such as will enable those skilled in the art to which it appertains to make and use the same.

The object of this invention is to provide an improved carpenter's vise, which may be connected with an ordinary carpenter's bench, and the construction and operation of which is such that the vise-jaw will be moved at both ends toward and from the bench and both ends thereof be held at exactly the same distance from the bench.

The invention is fully disclosed in the following specification, of which the accompanying drawings form a part, in which the separate parts of my improvement are designated by the same reference characters in each of the views, and in which—

Figure 1 is a sectional side elevation of my improved vise and showing the same connected with a carpenter's bench; Fig. 2, a back view thereof; Fig. 3, a section on the line 3 3 of Fig. 1; Fig. 4, a side view of a detail thereof, and Fig. 5 a partial section on the line 5 5 of Fig. 4.

In the drawings forming part of this specification I have shown at *a* a part of an ordinary carpenter's bench, and said bench is provided with a top plate *a*² and front or side plate *a*³, and in the practice of my invention I secure to the inside of the front frame of the bench a socket-piece *b*, which is screw-threaded internally to form a screw-threaded socket *b*².

The vise-jaw *c* is provided on the outside thereof with a plate *c*², which is secured thereto, and passing loosely through the jaw *c* is a screw *c*³, which also passes through the plate *c*² and into the socket *c*⁴ of a tubular cross-head *c*⁵, through which is passed a handle *c*⁶, and the screw *c*³ is secured in the shank *c*⁴, as shown at *c*⁷. The screw *c*³ is screw-threaded, as shown at *c*⁸, and passes loosely through an opening *c*⁹ in front of the bench, and the socket-piece *b* is threaded at *b*³ to correspond with the thread *c*⁸ on the shaft *c*³.

Screwed into the socket-piece *b* is a tubular sleeve *d*, which is provided with an external thread similar to the thread in the socket-piece *b*, and the screw *c*³ is provided, as shown in Fig. 3, with a longitudinal groove *d*³, and the sleeve *d* is provided with a corresponding lug or rib *d*⁴, and by means of this construction the sleeve *d* is locked to the screw *c*³.

Connected with the bench *a* below the top *a*² is a bracket or support *e*, from which is loosely suspended a lever *f*, composed of separate side members *f*², the lower ends of which are brought together at *f*³ and pivotally connected with a bar *f*⁴, which passes loosely through the front portion of the bench and into and through the lower end of the jaw *c* and is pivotally connected with said jaw at *f*⁵.

The outer end of the sleeve *d* is provided with a head *d*⁵, and the said sleeve is passed loosely through a disk or plate *g*, having side arms *g*², which pass through the sides *f*² of the lever *f*, and the head *d*⁵ of the sleeve *d* prevents said sleeve from being drawn from the disk or plate *g*, and a cup-shaped disk *h* incloses the head *d*⁵ of the sleeve *d* and is also provided with arms *h*², which pass through the sides *f*² of the lever *f* and preferably through the same opening through which the arms *g*² of the disk or plate *g* pass, and the cup-shaped disk *h* is provided with a central opening *h*³, through which the end of the screw *c*³ loosely passes. As thus constructed it will be seen that the sleeve *d* turns with the screw *c*³, and the lower end of the lever *f* is moved backwardly or forwardly, according to the direction in which the shaft is turned, and the length of said lever and its connection with the jaw *c* and the connection of the screw *c*³ with the jaw *c* is such that both ends of said jaw are moved toward and from the front side of the bench at the same time, and said ends of said jaw are always maintained exactly in the same relative position with reference to said front side of the bench *a*.

The separate sides *f*² of the lever *f* are connected by transverse rods *f*⁶ in the form of construction shown; but this lever may be of any preferred construction and may be suspended from the support or bracket *e* in any desired manner, and the thread on the screw *c*³ and the external thread on the

sleeve *d* are not of the same pitch, the number of threads to the inch being greater in the sleeve than on the screw, the difference in these threads depending on the length of the arms of the lever *f* with respect to each other.

My invention is not limited to the method of connecting the socket-piece *b* with the bench nor the position thereof, and changes ¹⁰ in and modifications of the construction described may be made without departing from the spirit of my invention or sacrificing its advantages.

Having fully described my invention, what ¹⁵ I claim as new, and desire to secure by Letters Patent, is—

1. The combination with a carpenter's bench of a socket-piece secured to the side thereof, a screw passing through said socket-piece, a sleeve secured to said screw and provided with a thread which engages a corresponding thread in the socket-piece, the threads in the sleeve and on said screw being of different pitches, a lever connected with ²⁰ said sleeve, a vise-jaw through which the front end of said screw passes, a handle-piece connected with said screw and a bar loosely connected with the lower end of said lever and

passing through the front of the bench and loosely connected with the lower end of the ³⁰ vise-jaw, substantially as shown and described.

2. In a carpenter's vise, a socket-piece secured to the front of a carpenter's bench, a screw passing through the front of the bench ³⁵ and through said socket-piece, said socket-piece and said screw being correspondingly threaded, a sleeve connected with said screw and threaded externally to correspond with a thread in the socket-piece of different pitch, ⁴⁰ a lever suspended rearwardly of said socket-piece and loosely connected with said sleeve, a vise-jaw through which the front end of said screw loosely passes a handle-piece connected with said shaft and a bar connected ⁴⁵ with the lower end of said lever and with the vise-jaw, substantially as shown and described.

In testimony that I claim the foregoing as my invention I have signed my name, in presence of the subscribing witnesses, this 25th day of June, 1902.

GEORGE WARREN DREW.
